UNITED STATES PATENT OFFICE.

OTTO MADER, OF DESSAU, GERMANY, ASSIGNOR TO HUGO JUNKERS, OF DESSAU, GERMANY.

SCAVENGING PUMP OF INTERNAL-COMBUSTION ENGINE.

Application filed October 29, 1931, Serial No. 511,400, and in Germany November 8, 1920.

My invention relates to internal combustion engines and more especially to the scavenging pumps combined with the pistons of such engines. It has particular reference to engines in which the single-acting piston of the scavenging pump is combined with the single-acting working piston of the engine.

It is an object of my invention to provide an engine which is simple in construction and smaller than older engines of equal power.

In engines of the kind mentioned above the diameter of the scavenging pump piston is considerably larger than the diameter of the working piston it is combined with. The scavenging air is forced from the pump into a receiver and from there into the working cylinder.

According to my invention, this arrangement is greatly simplified by conveying the scavenging air delivered by the pump into the chamber adjoining the rear face of the piston whereby the length, the weight and the costs of the engine are considerably reduced.

A further simplification obtained by arranging the delivery valves in the piston of the scavenging pump so that separate pipes connecting the pump with the receiver are dispensed with.

My invention can be applied with particular advantage to engines comprising pistons working in opposite directions, especially where both pistons operate on a common three-throw crank shaft.

In such engines the arrangement of a pump piston directly combined with the working piston presents particular difficulties inasmuch as a stepped pump piston so combined increases the width of the engine whereas, if the pump piston be attached to the outer working piston, the length, or in the case of vertical engines the height of the engine is considerably increased. With an arrangement of the pump piston as referred to last, my invention not only simplifies the design but also involves other important advantages, above all a considerable reduction in length or height.

In the drawings affixed to this specification and forming part thereof, several engines comprising pistons moving in opposite directions and embodying my invention are illustrated diagrammatically by way of example. In the drawings

Figs. 1 to 4 are sectional elevations, Fig. 1 being a horizontal twin shaft engine, and

Figs. 2 to 4 vertical three-throw crank shaft engines, while

Fig. 5 is a section on line V—V in Fig. 4, and

Fig. 6 is a sectional elevation of the upper portion of an engine of the old type.

In all the figures 1 is the working cylinder, 2 and 3 are the working pistons, 4 is the piston of the scavenging pump, 5 is the crank shaft or shafts, 7 (Figs. 2 to 6) is a cross head beam, 8 is the connecting rod of the inner piston 3, and 9 are the connecting rods of the outer piston 2. 12 are the scavenging and 13 the exhaust ports, 14 is the fuel inlet, 15 the cylinder of the scavenging pump, 16 are the suction and 17 the delivery valves of the scavenging pump, 20 is the receiver for the scavenging air and 21 the crank case.

Referring to Fig. 1, two crank shafts 5 are arranged at either end. The piston 4 of the scavenging pump is integral with the working piston 2. The scavenging pump cylinder is formed by that portion 15 of the crank case which surrounds the shaft 5 pertaining to piston 2. On the pistons moving inwards, air is drawn into chamber 15 through valve 16. On the return stroke, the air escapes through the delivery valves 17 arranged in the pump piston itself into the chamber 20 adjoining the pump piston and into which open the scavenging ports 12 of the working cylinder. In order to keep the variations of pressure during scavenging as low as possible, ports 23 are provided in the supporting walls 22 of the working cylinders so that the entire casing to the rear of the pump piston is utilized to form a receiver of great capacity for the scavenging air.

In the vertical engine disclosed in Fig. 2 the piston 4 of the scavenging pump is again integral with the working piston 2. Since the pump piston must be capable of supplying scavenging air to both working pistons 2 and 3, its diameter is so large that the connecting rods 9 which are here illustrated as engaging a cross head beam 7 of the outer piston 2, but may also be connected directly to the piston can be arranged within the cross-sectional area of the pump piston. This is practically impossible in the existing

type of engines inasmuch as the receiver surrounding the scavenging port does not permit the arrangement of such connecting rods in the immediate vicinity of the working cylinder. With the invention, however, the space in which the connecting rods of the outer piston 2 operate forms the receiver 20 for the scavenging air, as illustrated in Fig. 2. The receiver 20 is closed at its upper end by the rear face of the scavenging piston 4. The air delivered by the scavenging pump flows into the receiver 20 through valve 17 and pipe 18, and then enters the scavenging ports 12. The cross head beam 7 is disposed immediately below the scavenging pump piston 4 and is connected with the crank shaft 5 by the connecting rods 9. Openings 23 are formed in the wall 22 between the working cylinder 1 and the crank case through which the connecting rods 9 pass and which allow the whole casing 21 to be utilized as a receiver.

In the engine illustrated in Fig. 3 the pipe 18 is dispensed with and the delivery valves 17 are arranged in the scavenging pump piston 4 itself, so that the air drawn into chamber 15 on the downward stroke of piston 4 is discharged into the receiver 20 through valves 17 on the return stroke of the piston. This reduces to a minimum the resistance to the circulation of the scavenging air.

This engine is further provided with two scavenging ports 25 extending as far as the outer end of the working cylinder 1, so that the cross head beam 7 can enter them as it approaches the inner dead centre. Owing to this arrangement it is possible to place the piston 4 nearer to the scavenging ports 12, whereby a further reduction of the height or length of the engine is obtained.

In this engine as well as in the engine first described, the working cylinder 1 is supported in the casing 21 by a wall 22 provided with openings 23 for the connecting rods 9, so that here also the whole casing acts as a receiver for the scavenging air. The walls or partitions 22 further retain the oil splashed about by the crank shaft 5, loss of oil through the scavenging air being thus avoided as far as possible. If necessary, further baffles for retaining the oil may be arranged in the casing.

In order to entirely prevent losses of lubricating oil, I may use the arrangement illustrated in Fig. 4. Here, the cross head beam 7 is not directly connected with the crank shaft by means of connecting rods 9, but rods 11, which are guided by cross heads 10, are inserted between the beam 7 and the connecting rods 9, the passages managed for these rods in the partitions 22 being so narrow or so well packed that no scavenging air can enter the casing 21, only the chamber 20 forming the receiver for the air.

In the engine illustrated in Fig. 4, the

stroke of the outer piston 2 is considerably shorter than that of the inner piston 3. Pistons moving in opposite directions with different stroke have been utilized before to reduce as far as possible the inertia effects in the two gears. In the present case, however, the stroke of the scavenging pump piston 4 is reduced also so that it is possible to design this piston with a large diameter without its supplying too much air and causing unnecessary loss of power. This involves the further advantage that the parts serving to actuate the outer piston can be easily arranged within the cross-sectional area of the pump piston, which would otherwise be impossible, in some types of engines and more particularly in engines having a long stroke.

In the engines illustrated in Figs. 2 to 4, no means are provided for preventing the pistons 2 and 4 and the parts actuating them from turning about the axis of the pistons. In order to prevent such turning movement, the piston 4 may be provided with an axial groove 28 as illustrated in Fig. 5, and the pump cylinder with a corresponding axial projection 29.

The variations of pressure which occur in the scavenging air receiver owing to the operation of the piston 4, can be reduced in multicylinder engines with cranks at different angles by interconnecting the receivers of the several cylinders.

The reduction of height or length of the engine and the simplification of design obtained by aid of the present invention are best illustrated by a comparison with Fig. 6, in which an engine of usual design is illustrated having the same proportions as the engine illustrated in Fig. 4. The scavenging pump 15 delivers into a receiver 30 surrounding the scavenging ports 12. The cross head beam 7 which projects on both sides must be disposed at a distance h_1 below the pump piston equal to the stroke of this piston in order to keep the slots 31 in which the beam is guided apart from the interior of cylinder 15. The cross head cannot be so arranged as to enter extended scavenging ports of the working cylinder 1, as it operates in the open air, from which the scavenging air receiver 30 must be separated. The working piston 2 must therefore be elongated for about the distance h_2 from the inner edges of the scavenging ports 12 to the upper end of the cylinder. The length or height of an engine of the usual design is, therefore, reduced in accordance with the present invention by the total of the distances h_1 and h_2 , and, at the same time, the design of the engine is much simplified.

I wish it to be understood that I do not desire to be limited to the exact details of construction shown and described, for obvious modifications will occur to a person skilled in the art.

I claim:

1. In an internal combustion engine in combination, a working cylinder, a working piston in said cylinder, a single acting scavenging pump piston of larger diameter connected with said working piston, and a closed scavenging air pump cylinder surrounding said pump piston and an inlet and an outlet valve in one half of said pump cylinder and communication between said outlet valve and the inlet of said working cylinder through the other half of said pump cylinder. 70
2. In an internal combustion engine in combination, a working cylinder, a working piston in said cylinder, a single acting scavenging pump piston of larger diameter connected with said working piston, and a closed scavenging air pump cylinder surrounding said pump piston, an inlet and an outlet valve in one half of said pump cylinder and communication between said outlet valve and the inlet of said working cylinder through the other half of said pump cylinder, a crank shaft and a connecting rod extending through that part of said pump cylinder which is connected to the inlet of said working cylinder and connecting one of said pistons to said shaft. 80
3. In an internal combustion engine in combination, a working cylinder, a working piston in said cylinder, a single acting scavenging pump piston of larger diameter connected with said working piston, and a closed scavenging air pump cylinder surrounding said pump piston, an inlet valve in one half of said pump cylinder, an outlet valve forming part of said pump piston adapted to govern the communication between the inner and outer parts of said pump cylinder, and communication between one of said parts and said working cylinder. 90
4. In an internal combustion engine in combination, a working cylinder, two working pistons in said cylinder adapted to move in opposite directions, a crank shaft and a connecting rod connecting said shaft with one of said pistons, another connecting rod connecting said shaft with said second piston, a single acting scavenging pump piston of larger diameter rigidly connected with said second piston, and a closed scavenging air pump cylinder surrounding said pump piston and an inlet and an outlet valve in one half of said pump cylinder and communication between said outlet valve and the inlet of said working cylinder through the other half of said pump cylinder. 100
5. In an internal combustion engine in combination, a working cylinder, two working pistons in said cylinder adapted to move in opposite directions, a crank shaft and a connecting rod connecting said shaft with one of said pistons, a cross head beam connected with said second piston, a pair 110
6. In an internal combustion engine in combination, a working cylinder, two working pistons in said cylinder adapted to move in opposite directions, a crank shaft and a connecting rod connecting said shaft with one of said pistons, a single acting scavenging air pump piston of larger diameter connected with said second piston, a cross-head beam arranged close to the rear face of said pump piston, a pair of connecting rods connecting said shaft with said beam, and a closed scavenging air pump cylinder surrounding said pump piston and an inlet and an outlet valve in one half of said pump cylinder and communication between said outlet valve and the inlet of said working cylinder through the other half of said pump cylinder. 120
7. In an internal combustion engine in combination, a crank case, a working cylinder, a working piston in said cylinder, a single acting scavenging pump piston of larger diameter connected with said working piston, and a closed scavenging air pump cylinder surrounding said pump piston, and an inlet and an outlet valve in one half of said pump cylinder and communication between said outlet valve and the inlet of said working cylinder through the other half of said pump cylinder and said crank case. 130
8. In an internal combustion engine in combination, a crank case, a working cylinder, two working pistons in said cylinder adapted to move in opposite directions, a crank shaft and a connecting rod connecting said shaft with one of said pistons, a single acting scavenging air pump piston of larger diameter connected with said second piston, a cross-head beam arranged close to the rear face of said pump piston, a pair of connecting rods connecting said shaft with said beam, and a closed scavenging air pump cylinder surrounding said pump piston, and an inlet and an outlet valve in one half of said pump cylinder and communication between said outlet valve and the inlet of said working cylinder through the other half of said pump cylinder and said crank case. 140
9. In an internal combustion engine in combination, a crank case, a working cylinder, two working pistons in said cylinder adapted to move in opposite directions, a crank shaft and a connecting rod connect-

ing said shaft with one of said pistons, a single acting scavenging air pump piston of larger diameter connected with said second piston, a cross-head beam arranged close to the rear face of said pump piston, a pair of connecting rods connecting said shaft with said beam, and a closed scavenging air pump cylinder surrounding said pump piston, an inlet and an outlet valve in one half of said pump cylinder and communication between said outlet valve and the inlet of said working cylinder through the other half of said pump cylinder and said crank case and a partition intermediate that part of said pump cylinder which is connected to the inlet of said working cylinder and said crank case offering an oil-tight passage for said connecting rod.

10. In an internal combustion engine in combination, a crank case, a working cylinder, a working piston in said cylinder, a single acting scavenging pump piston of larger diameter connected with said working piston, and a closed scavenging air pump cylinder surrounding said pump piston, a crank shaft, a connecting rod connecting said shaft with one of said pistons, an inlet and an outlet valve in one half of said pump cylinder and communication between said outlet valve and the inlet of said working cylinder through the other half of said pump cylinder and said crank case and a partition intermediate that part of said pump cylinder which is connected to the inlet of said working cylinder and said crank case offering an oil-tight passage for said connecting rod.

11. In an internal combustion engine in combination, a working cylinder, two working pistons in said cylinder adapted to move in opposite directions, a crank shaft and a connecting rod connecting said shaft with one of said pistons, a cross head beam connected with said second piston, a pair of connecting rods connecting said shaft with said beam, scavenging ports in said working cylinder, a pair of open slots in said cylinder extending down to said ports in line with said beam, a single acting scavenging pump piston of larger diameter rigidly connected with said second piston, and a closed scavenging air pump cylinder surrounding said pump piston and an inlet and an outlet valve in one half of said pump cylinder and communication between said outlet valve and the inlet of said working cylinder through the other half of said pump cylinder.

12. In an internal combustion engine in combination, a working cylinder, a working piston in said cylinder, a single acting scavenging pump piston of larger diameter connected with said working piston, and a closed scavenging air pump cylinder surrounding said pump piston, an inlet and an outlet valve in one half of said pump cylinder and communication between said outlet valve and the inlet of said working cylinder through the other half of said pump cylinder and means for preventing circumferential movement of said pistons.

In testimony whereof I affix my signature.

OTTO MADER.
